CARBURETOR STRUCTURE

Irven E. Coffey, St. Louis, Mo., assignor to Carter
Carburetor Corporation, St. Louis, Mo., a cor-
poration of Delaware

Application June 28, 1938, Serial No. 216,225

2 Claims. (Cl. 261—34)

This invention relates to carburetors for internal combustion engines and consists particularly in novel accelerating and idling means therefor.

5 A co-pending application, Serial No. 173,143 filed November 6, 1937, in the name of the present inventor discloses and claims a carburetor having independent main nozzle and idling systems, the latter being provided with an air bleed controlled by a loaded check valve. This valve is adapted to open when relatively high suctions prevail in the idling system so as to substantially lean out the fuel mixture supplied by the idling system, and to close when relatively low suctions prevail in the idling system whereby the idling mixture is enriched. The arrangement shown results in discharge from the carburetor of a richer, more powerful fuel mixture at low suctions with the throttle partly open than is the case where the main nozzle and idling systems are interconnected, while at the same time providing for proper metering of fuel under normal idling and part throttle operation when the idling port is exposed to relatively high suctions and less fuel is needed. An automotive carburetor is preferably provided with an accelerating device in addition to the main nozzle and idling systems.

In the present invention, an idling system, as described in the above mentioned application is combined in a novel manner with the accelerating pump.

Accordingly, it is an object of the present invention to combine, in a simple construction, the idling and accelerating systems in a carburetor.

A more detailed object is to provide an accelerating system for a carburetor discharging adjacent the throttle valve and including an inlet check adapted to be opened by normal idling suctions in the system to provide idling fuel.

Another detailed object is to provide an accelerating system for carburetors which discharges adjacent to and posterior to the throttle and otherwise arranged to function as an idling system when the throttle valve is closed.

These objects and other more detailed objects are attained by the structure illustrated in the accompanying drawing in which:

Fig. 1 is a side view, partially broken away and sectioned, of a carburetor embodying a form of the invention.

Fig. 2 is an enlarged sectional view showing a detail of the structure of Fig. 1, and

Fig. 3 is a detail horizontal section taken substantially on the line 3—3 of Fig. 2.

Fig. 4 is a perspective view of the valve cage shown in section by Fig. 2.

The carburetor shown comprises a downdraft mixture conduit, including an air inlet horn 1, venturis 2, 3 and 4, mixing chamber 5, and outlet portion 6, flanged as at 7 for attachment to the intake manifold (not shown) of an associated internal combustion engine. Adjacent the mixture conduit is a bowl 8 within which a supply of gasoline is maintained at a substantially constant level by needle valve mechanism 9, controlled by a float 10. The needle valve controls the entry of fuel into the carburetor bowl from a remote supply. Fuel is supplied to the mixture conduit through a calibrated orifice member 11, 15 frequently called the jet, and main nozzle 12 discharging into the throat of the smallest venturi 2. Orifice member 11 is controlled by a stepped metering rod 13, operated from throttle valve 14 by means of an arm 15, a link 15a and a lever or 20 rocker arm 16. Rod 13 is yieldingly connected to the lever 16, as at 17 and is provided with an enlargement 18 adapted to seat against the upper surface of orifice member 11 when the throttle valve is fully closed to prevent the passage of fuel 25 from bowl 8 into the main nozzle.

A cylinder 19 depends into another part of bowl 8 from cover portion 20 thereof and slidably receives a piston 21 controlled from the throttle valve by means of an arm 22, which may be rigid 30 with or a part of arm 15, a link 23, a pivoted lever 24 and rod 25. Cylinder 19 communicates with the interior of bowl 8 through a passage 26 in the bottom wall thereof, this wall having an internal, annular ridge 27 surrounding passage 26 35 and forming a seat for disc check 28. Valve 28 also constitutes the major part of the bottom wall of the pump cylinder. Cylinder 19 communicates with the mixture conduit through passages 29, 30 and 31 and a port 32 in the wall of 40 the mixture conduit adjacent and posterior to the edge of throttle valve 14 when the valve is closed. A calibrated restriction 33 is provided in passage 30. Passages 30 and 31 communicate with the mixture conduit anterior to venturis 2, 45 3 and 4 by means of air bleed holes 34 and 35. Air bleed 34 is controlled by a check disc 36 normally urged upwardly to close the air bleed by means of a coiled spring 37, supported on a pin 50 in passage 30.

In operation, cylinder 19 and piston 21 comprise a pressure chamber and movable wall for drawing fuel into the chamber and expelling the same therefrom and these, with passages 29, 30 and 31, comprise an accelerating system for sup- 55

plying a charge of accelerating fuel through port 32 when the throttle valve is opened. Closing of the throttle valve lifts piston 21, drawing a supply of liquid fuel from the bowl or reservoir past inlet valve 28 into the pump pressure chamber in the lower part of cylinder 19. Piston 21 is returned to its upper or charged position by a coiled spring 39 seated at the bottom against a flanged portion 40 on cage 41 provided for maintaining the check disk 28 in its proper relation with valve seat ridge 27.

Passages 29, 30 and 31 and port 32 also function as an idling system for supplying a small quantity of combustible mixture to the mixture conduit when the throttle valve is closed. The weight of disc check 28 is such as to permit lifting of this disc when relatively high suction exists in passage 31 to permit normal functioning of the idling system and may be designed to close when less suction prevails in passage 31, as when the throttle is opened sufficiently to cause aspiration of fuel from the independent main nozzle. Bleed check 36 and spring 37 are calibrated to open air bleed 34 into the idling system only under higher suction in passage 31 than is sufficient to open disc check 28, that is, when lower pressures exist in the idling system so as to stop or decrease the discharge of fuel through passage 31 and port 32 at such time. This disc 36 functions, as explained in the above-mentioned co-pending application, to lean out the idling discharge under normal idling and part throttle operation and to cut off the air bleed when exposed to relatively low suction conditions to provide better power for part throttle operation. Disc checks 36 and 28 are both closed during discharge of the accelerating pump. Air bleed 35 is positioned relative to passage 30 so that no gasoline will escape therethrough during discharge of the pump. Since the suction at port 32 will exceed that to which air bleeds 34 and 35 are exposed, whenever the throttle valve is partly closed, there will be a continual draft of air downwardly through passage 31 and port 32 to assist in carrying the accelerating charge into the mixture conduit and in vaporizing the same.

Enlargement 18 on metering rod 13 cooperates with calibrated orifice member 11 when the throttle valve is closed to prevent flowing of liquid fuel from bowl 8 out through the main nozzle, such as frequently occurs after a hot engine is stopped due to boiling of the fuel in the restricted chamber at the base of the nozzle, this action being known as "percolation."

The arrangement shown attains the advantages of an independent idling and main nozzle construction, as set forth in the above-mentioned co-pending application, and, in addition, provides a greatly simplified combination idling and accelerating system whereby a number of previously necessary parts are eliminated without the loss of function. I have shown the accelerating pump piston as actuated from the throttle valve, but this is not necessary and the piston may be otherwise actuated, if desired. The general features of the carburetor, as shown, are not essential and the arrangement of the various passages and other features may be varied as will occur to those skilled in the art. The exclusive use of all such modifications as come within the scope of the appended claims is contemplated.

I claim:

1. In a carburetor, a mixture conduit having a throttle valve, a constant level fuel reservoir, an accelerating pump including a vertically arranged cylinder and a piston therein, a fuel inlet passage extending from the lower portion of said cylinder into said reservoir below the normal level therein, a combined idling fuel system and discharge nozzle for said accelerating pump comprising a passage extending from said cylinder to an idling port in the wall of said mixture conduit on both sides of said throttle valve when closed, and an inlet check in said inlet passage adapted to admit fuel when said piston is moved in the charging direction as well as when the carburetor is in operation with said throttle valve in idling position.

2. In a carburetor, a mixture conduit, a butterfly throttle valve therein, there being idling port means located in the wall of said conduit so as to straddle the edge of said throttle when closed, a constant level fuel reservoir, an accelerating pump including a cylinder extending below the normal level in said reservoir and a piston, there being an inlet passage between said cylinder and said reservoir below the normal level therein, a discharge passage connecting said cylinder adjacent said inlet passage and said idling port means, and an inlet check valve in said inlet passage constantly exposed to fluid pressure conditions in said cylinder whereby fuel will be discharged solely through said discharge passage and port means upon actuation of said piston and whereby idling fuel may be drawn through said inlet passage, cylinder, and discharge passage.

IRVEN E. COFFEY.
